UNITED STATES PATENT OFFICE.

JOSEPH BARRAJA-FRAUENFELDER, OF BRIDGEPORT, CONNECTICUT, ASSIGNOR TO THE
LAKE TORPEDO BOAT COMPANY OF MAINE, OF BRIDGEPORT, CONNECTICUT, A
CORPORATION OF MAINE.

SUBMARINE BOAT.

1,190,210.

Specification of Letters Patent. Patented July 4, 1916.

Application filed December 15, 1914. Serial No. 877,409.

To all whom it may concern:

Be it known that I, JOSEPH BARRAJA-FRAUENFELDER, a citizen of the United States, residing at Bridgeport, in the county 5 of Fairfield and State of Connecticut, have invented certain new and useful Improvements in Submarine Boats, of which the following is a specification.

Modern submarine or submersible torpedo boats are so increasing in size that it is 10 found impracticable to handle the usual hand operated valves now employed for controlling the admission of sea-water into the main ballast-tanks so as to bring the boats 15 from the surface to the "awash" condition within the specified time for effecting this operation, this being due to the fact that the larger types of boats possess greater surface buoyancy, necessitating larger ballast- 20 tanks, and relatively larger sea-valves, in order to trim the boat for submergence within the time required.

The object of the invention is to greatly 25 simplify the apparatus for controlling the admission of water-ballast to the main ballast-tanks, and by which water may be quickly and conveniently admitted to the tanks to thus fulfil the requirements of the larger types of boats now being constructed.

30 The invention consists in providing a submarine or submersible boat with a manifold arranged within the main ballast-tank and opening to the water of flotation through two openings controlled by outwardly opening hand operated sea-valves, and also opening 35 into the ballast-tank through a single opening controlled by an inwardly opening and preferably power operated valve of an area substantially equal to the combined 40 area of the two sea-valves, the construction, arrangement and operation being such that the sea-valves are first opened by hand power operated devices to admit water into the manifold, when the boat is being made 45 ready for submergence, and from which manifold the water may quickly be admitted to the ballast-tank when the moment arrives to put the boat into submerging condition, that is to say, into condition ready for final 50 trim and complete submergence.

The invention further consists in the peculiar and novel features of construction, combination, and arrangement of parts as

will be hereinafter fully described and then claimed.

In the drawings illustrating the invention, in the several figures of which like parts are similarly designated, Figure 1 is a diagrammatic side elevation of a submarine torpedo boat having the outer hull partly broken away to illustrate the location of my invention. Fig. 2 is a transverse section of the same drawn on the line *a—a* of Fig. 1. Fig. 3 is a transverse section on a larger scale drawn on the line *b—b* of Fig. 1. Fig. 4 is a detail longitudinal section drawn on the line *c—c* of Fig. 3. Fig. 5 is a similar view drawn on a larger scale on the line *d—d* of Fig. 3. Fig. 6 is a horizontal section drawn on a larger scale on the line *e—e* of Fig. 3. Fig. 7 is a vertical transverse section drawn on the line *f—f* of Fig. 6. Fig. 8 is a horizontal section drawn through one of the devices for operating the outwardly opening sea-valves. Fig. 9 is a vertical section of the same drawn on the line *g—g* of Fig. 8.

1 designates the outer hull of a submarine or submersible torpedo boat, and 2 the inner or main hull thereof. The space 3 thus formed between said hull section is divided by transverse partitions or bulkheads 3' providing a water ballast compartment commonly known as a tank, and in the present construction constitutes the main ballast-tank. It may be stated here, that while my invention is illustrated in connection with a double hull boat, it is not to be understood that I limit myself to this design of hull, as the invention will be found equally applicable to single hull boats in which the main ballast-tanks are built within the main hull. Within the tank 3, and connected air- and water-tight to the hull sections 1 and 2, is a manifold 4 having a horizontal partition 5 providing an upper chamber 6 and a lower chamber, the latter being divided by vertical longitudinally arranged partitions 7, which are connected air- and water-tight to the plate of the outer hull 1, providing a central duct 8 in open communication at its ends with the ballast-tank 3, and two end compartments 9, which are closed at their sides and in open communication with the water of flotation through openings 10 formed in the plating of the outer hull 1. The compartments 9 communicate with the

chamber 6 through openings 11 formed in the said horizontal partition 5, and are controlled by outwardly opening sea-valves 12, the stems 12' of which extend upwardly 5 through the partition 5, and through stuffing-boxes 13 connected thereto, and have their upper ends terminating in slotted heads 14 providing trammels. As the head of each valve stem and the mechanism for operating the valves is exactly alike I shall describe only one and will place the reference characters on the corresponding parts of both.

Each head 14 is formed with a right-
15 angular opening 15, providing a cam slot, in the vertical end 15' of which is held a cam-block 16 carried by a shaft 17 having its ends journaled in bearings 18' formed in a bracket 18 secured to the lower side of a horizontal
20 partition 191 arranged in the inner or main hull section 2 of the boat. Keyed upon the shaft 17, at each side of the head 14, are lever-arms 19 in the free ends of which is journaled a short shaft 19' carrying a cam-
25 block 20 which is designed to operate in the horizontal end 15'' of the cam slot 15, and upon one end of the shaft 17 is keyed a seg-
30 mental worm-wheel 21 which is meshed by a drive-worm 22 carried by a shaft 23 jour-
naled at its lower end in a bearing 24 secured to the lower side of the partition 191, and having its upper end extended through said partition and mounted in a suitable bearing
35 mounted upon the top of the said parti-
30 tion 191, and provided with a hand wheel 26. By the mechanism just described, it will be apparent, that as the shafts 23 are rotated in one direction or the other, the seg-
35 mental worm-wheels 21 will be rotated to
40 thus cause the cam-blocks 20 to slide in the horizontal end 15'' of the cam slots to thus impart a vertical reciprocating motion to the valve stems to open or close the valves 12, as the case may be. It will also be apparent
45 that by thus gearing the operating shafts to the valve stems I obtain great leverage, and hence, am enabled to operate the valves with
but little energy.

The channel or duct 8 communicates with
50 the chamber 6 through an opening 8' formed in the partition 5, the opening being controlled by an inwardly opening valve 28 to which is swiveled the lower end of a piston-
55 rod 29 carried by a piston 29' operating in a cylinder 30 mounted in the main hull sec-
60 tion 2 below the partition 191. The lower end of the rod 29 operates through a stuffing-
65 box 31 secured to the top 4' of the manifold and has its upper end extended through the head of the cylinder 30 and through a stuff-
ing-box formed thereon, and its extreme upper end threaded as shown at 31' Fig. 7 for the purpose hereinafter appearing. Fluid under pressure, which may be air, oil,
85 or water, is admitted to the opposite ends of

the cylinder 30 through a branch pipe 30'
Fig. 3 extending from a suitable source of supply (not shown) and in which is arranged a two-way valve 30'', which, for convenience of illustration, is shown located adjacent to the cylinder, but which may be arranged in the central control station, or conning-tower, or in any other convenient place within the boat. It will be understood that when fluid under pressure is admitted to the lower end of the cylinder 30, the valve 28 will be lifted from its seat to thus permit the water in the chamber 6 of the manifold to flow into the ballast-tank.

In order to operate the valve 28 by hand
80 in the event of accident to the power operating devices, I mount a threaded sleeve 31' upon the threaded section 31' of the piston-
85 rod and upon the periphery of the sleeve I mount a worm-wheel 32 which is held against vertical movement by a bracket 33 extending from the head of the cylinder 30, and by channel bars 34 secured to the lower side of the partition 191. The hub of the worm-wheel 32 is made in sections and 90 comprises a semi-circular section 35 Fig. 6 which is formed integral with the rim of the wheel and a loose section 36 which is carried by bolts 37 extending through diametrically disposed ribs or spokes connecting the rigid 95 section of the hub with the rim of the wheel, said bolts having clamping nuts threaded upon their outer ends by which the loose section of the hub may be clamped against the sleeve and the wheel thus clamped upon the sleeve so as to cause the sleeve to rotate with the wheel. The worm-wheel 32 is meshed by a worm 38 mounted in a bracket 39 supported by the partition 191 and has its shaft provided with a hand wheel 40, Figs. 3 and 6. 100 By this arrangement it will be evident that when the wheel 32 is clamped upon the sleeve and the worm 38 is operated, the sleeve will be rotated and because said sleeve and the wheel 32 are held against vertical movement, 105 the valve 28 will be opened or closed as the case may be.

In order to prevent the operation of the valve 28 until after the sea-valves 12 have been opened I connect the stems of the sea-
115 valves to one end of elbow levers 41 which are pivotally mounted upon brackets 24' and to the opposite ends of the levers are connected locking pins or rods 42 having their free ends extending through guides 43 120 formed in the bracket 33 and adapted for engagement with an annular groove 44 formed in the upper end of the piston-rod 29. By this arrangement it will be seen that when the valves 12 are opened the 125 elbow levers 41 will be rocked in the direction indicated by the arrows in Fig. 3 to thus withdraw the ends of the locking pins or rods from the groove 44 in the piston-rod so that the valve 28 then may be opened. 125

In operation the sea-valves 12 are first opened by hand as previously described to first admit the water of flotation to enter the chamber 6 of the manifold, so that, when 5 the vessel has been made ready for submergence, the inwardly opening valve 28 may be operated to permit the water to flow into the ballast-tank 3. It will thus be seen that I provide an exceedingly simple and 10 compact arrangement for controlling the admission of water ballast to the ballast-tanks of submarine boats, and by providing two sea-valves instead of only one, I am enabled to construct them of such size as to facilitate their operation by hand, and at the 15 same time I am enabled to provide a single power-operated valve of a size equal in area to the two sea-valves, so that water ballast may be quickly let into the ballast-tanks. It 20 will be noted that all of the valves open against the pressure of the water of flotation and that when the tank is being pumped or blown the valve 28 will be automatically lifted from its seat should pressure upon the piston 29 be relieved, it of 25 course being understood that the worm-wheel 32 is unlocked from the sleeve 35.

The compartments 9 are covered as usual by perforated plates 50 forming screens, to 30 prevent foreign matter, such as sea-weed from getting into contact with the valves 12 and their seats and interfering with the tight seating of the valves.

What I claim is:

- 35 1. A submarine or submersible boat, having a tank to contain water-ballast, a manifold arranged in and communicating with said tank and with the water of flotation, outwardly opening valves controlling the admission of sea-water to said manifold, and an inwardly opening valve controlling the communication between said manifold and said tank.
- 40 2. A submarine or submersible boat, having a tank to contain water-ballast, a manifold arranged in said tank and communicating therewith through a single opening and with the water of flotation through two openings, the combined area of said latter openings being substantially equal to that of the opening leading to the said tank, an inwardly opening valve controlling the admission of water to said ballast-tank, and outwardly opening sea-valves controlling the admission of water to the manifold.
- 45 3. A submarine boat, having a tank to contain water-ballast, a manifold arranged in and communicating with said tank through a single opening and with the water of flotation through two openings, a power-operated inwardly opening valve controlling the opening leading to the tank, and outwardly opening, hand operated valves controlling the admission of sea-water to the manifold.
- 50 4. A submarine or submersible boat, having a tank to contain water-ballast, a manifold arranged in said tank and having a horizontal partition providing a chamber, a duct below said partition opening into the tank, valve controlled openings formed in said horizontal partition and opening to the water of flotation, a valve controlled opening formed in said partition and opening into the duct, and means for operating said valves. 70
- 55 5. A submarine or submersible boat, having a tank to contain water-ballast, a manifold arranged in said tank and having two compartments which are in open communication with the water of flotation, and a channel or duct in open communication with said tank, outwardly opening sea-valves controlling the admission of sea-water to said manifold, and a single inwardly opening valve controlling the admission of water to said tank through said manifold, and independent means for operating said valves. 80
- 60 6. A submarine or submersible boat, having a tank to contain water-ballast, a manifold arranged in said tank and having two compartments in open communication with the water of flotation and a single duct in open communication with said tank, outwardly opening sea-valves controlling the admission of sea-water to the manifold, hand operated mechanism for operating said sea-valves, a valve controlling the admission of water to the tank from said manifold, power operated means for operating said valve, and a hand operated device adapted to co-act with said power operated device, as and for the purpose specified. 90
- 65 7. A submarine or submersible boat, having a tank to contain water-ballast, a manifold arranged in said tank and having two compartments communicating with the water of flotation and a single opening communicating with said tank, the area of the latter opening being substantially equal to the combined areas of the first-mentioned openings, and co-operative valves for controlling said communications. 105
- 70 8. A submarine or submersible boat, having a tank to contain water-ballast, a manifold arranged in said tank and having two compartments in open communication with the water of flotation and a duct in open communication with said tank, and valves controlling the flow of water through said manifold, substantially as described. 110
- 75 9. A submarine or submersible boat, having a tank to contain water-ballast, a manifold arranged in said tank and having a communicating chamber and duct, said duct being in open communication with said tank, and two compartments communicating with said chamber, said compartments being in open communication with the water of flotation, valves controlling said commu- 125
- 80 10. A submarine or submersible boat, having a tank to contain water-ballast, a manifold arranged in said tank and having a communicating chamber and duct, said duct being in open communication with said tank, and two compartments communicating with said chamber, said compartments being in open communication with the water of flotation, valves controlling said commu- 130

nications, and independent means for operating said valves.

10. A submarine or submersible boat, having a tank to contain water-ballast, a manifold arranged in said tank and having a chamber communicating therewith through a single opening and with the water of flotation through two openings, an inwardly opening power operative valve controlling the opening leading to the tank, a hand operative device adapted to be operatively connected to said valve, for the purpose specified, and outwardly opening hand operated valves controlling the openings leading to the water of flotation.

11. A submarine or submersible boat, having a tank to contain water-ballast, a manifold arranged in said tank and communicating therewith through a single opening and with the water of flotation through two openings, an inwardly opening valve controlling the communication between said manifold and said ballast-tank, means for operating said valve, outwardly opening sea-valves controlling the admission of sea-water to said manifold, means for operating said sea-valves, and locking means

for preventing the operation of the valve controlling the admission of water to the ballast-tank.

12. A submarine or submersible boat, having a tank to contain water-ballast, a manifold arranged in said tank and communicating therewith through a single opening and with the water of flotation through two openings, an inwardly opening valve controlling the communication between said manifold and said ballast-tank, means for operating said valve, outwardly opening sea-valves controlling the admission of sea-water to said manifold, means for operating said valves, and locking means for preventing the operation of the valve controlling the admission of water to the ballast-tank, said means being operable by and through the operation of said sea-valves.

In testimony whereof I have hereunto set my hand this 14th day of December, A. D. 1914.

JOSEPH BARRAJA-FRAUENFELDER.
